UNITED STATES PATENT OFFICE.

JAMES STANLEY BISHOP, OF CINCINNATI, OHIO.

CAMERA.

1,415,514.

Specification of Letters Patent. Patented May 9, 1922.

Application filed September 11, 1916. Serial No. 119,472.

To all whom it may concern:

Be it known that I, JAMES STANLEY BISHOP, a citizen of the United States, and a resident of Cincinnati, in the county of Hamilton and State of Ohio, have invented certain new and useful Improvements in Cameras, of which the following is a specification.

My invention relates to photography, and its object is to facilitate the application of indicia to the sensitized surface while in the camera.

My invention consists in the combination of parts and in the details of construction and arrangement of parts as will hereinafter be more fully described and claimed.

In the drawings:

Fig. 1 is the front elevation of the upper part of a film camera in which my invention is incorporated, the camera being represented as being open;

Fig. 2 is a rear elevation of the same with part of the back and film broken away;

Fig. 3 is a horizontal cross-section on a plane corresponding to the line 3-3 of Fig. 2;

Fig. 4 is a vertical longitudinal section on a plane corresponding to the line 4-4 of Fig. 2;

Fig. 5 is a similar view but showing the camera closed;

As shown in the drawings, my invention is incorporated in a film camera of well known type, comprising a casing 1 made up of sides 2 and 3, which are generally made of wood, and upper and lower shells 4 and 5 extending from the side 2 to the side 3 and around the upper and lower ends of these sides, and with parts turned in between the sides at the top and bottom forming partitions 6 and 7, respectively, to define the chambers for the film-winding spool 8 at the top and film-feed spool 9 at the bottom, respectively, with the bellows chamber 10 in the middle. This latter is open, with a leaf 11 hinged at the lower end to drop down as shown in Fig. 4, or to be raised and thus close the opening as shown in Fig. 5. The upper and lower partitions 6 and 7 are provided at the front with off-sets 12 and 13, respectively. The lower off-set 13 contains the hinge for the leaf 11; and in the upper off-set 12, I locate the catch 14 which

holds the leaf 11 up in closed position; this catch 14, as here shown, being a piece of resilient metal extending down from a small recess 15 above and at the middle of said off-set 10.

As these cameras are usually constructed, they have both ends rounded like the lower end as shown in Figs. 4 and 5; and the shells extend only half way around the ends of the wooden sides 2 and 3, as does the lower shell 5 in my example. I modify the construction of the upper end by making it flat, and with the upper shell 4 extending entirely back to the rear edges of the wooden sides 2 and 3, where it is provided with a ledge 16 somewhat like the ledge 17 of the usual design at the rear edge of the lower shell 5. A back 18, with its lower end curved and with a flange 19 fitting under the ledge 17, and with its upper end merely provided with the flange 20 to fit under the ledge 16, has the usual side flanges 21 (Fig. 3) fitting into grooves 22 in the rear edges of the wooden sides 2 and 3. The partitions 6 and 7 fit into grooves in the inner sides of the ends 2 and 3, as illustrated in Figs. 2 and 3.

Inside the bellows chamber 10 is the bellows 23 with its front end suitably secured to the mounting 24 (Fig. 5) that carries the lens and shutter, and with its rear end secured at the bottom to a transverse part 25 at the rear end of the partition 7, and at its sides in upright metal parts 26 fitting closely against the wooden sides 2 and 3. As these cameras are usually constructed, the top of the rear end of the bellows 23 is secured to the upper partition 6 by a part 27 like the part 25 by which the bottom is secured to the lower partition 7. In my invention, however, the bellows does not extend to the upper partition 6. A partition 27 runs across from one wooden end to the other, being fitted in grooves in said ends and being located a distance downward from the partition 6 to define an operating space 28; this distance being determined by the desired height of the space reserved for the indicating marks on the sensitized surface, as imposed by the details of construction which will presently be described.

It is to this partition 27, near the rear edge thereof, that the top of the rear end of the bellows 23 is secured; this being done by

means of a flat strip 29 that extends from side to side of the camera and makes close connection with the upright parts 26. This strip 29 is rigidly held up on the partition 27 with the bellows material interposed between it and said partition. Also interposed between these parts 27 and 29 is a strip 30 of soft flexible material, such as soft leather, which extends past the rear edges of the partition 27 and strip 29 entirely across the camera from one upright part 26 to the other. The back 18 has a forwardly pressed part 31 preferably covered by a piece 32 of soft material such as soft leather, through-out the area of the rear end of the operating space 28. The film 33 passes from the feed-spool 9 up over a lower roller 34 and along the upright parts 26 at the rear of the bellows, against which its parts near its edges are held by upright flat spring strips 33' on the inside of the back 18, (Figs. 3, 4 and 5) which, in my invention, are preferably discontinued just below the forwardly pressed part 31 of said back 18. The film 33 then passes between the leather pieces 30 and 32 on the partition 27 and part 31, respectively, and past the rear end of the operating space 28, and then up over the upper roller 35 to the winding-spool 8.

From the foregoing it will be seen that the film 33 is arranged and travels in the same way that it does in all cameras of this type, except that it passes in intimate contact with the soft flexible piece 30; its sensitized front surface making contact with the rear edge of the piece 30 and its back being supported by the forwardly pressed part 31 of the back 18. This back 18 is removably held on the camera by the usual latches 36 at the sides (Figs. 3, 4 and 5).

Thus, the area that is to contain the picture, as distinguished from that containing the title or other indicating marks at the bottom of the picture, is defined at the bottom of the picture by the contact of the piece 30 with the sensitized surface. The bellows, with its usual mountings made up of the parts 26 against the side parts of the film and the part 25 very close to the film, excludes all light except that entering through the lens; and the piece of flexible material 30 making intimate contact with the sensitized surface without marring it, performs this function at the top of the bellows.

Thus, the operating space 28 is adapted to admit light to the small part of the sensitized surface at its rear end; the light entering from the open front of the camera casing 1 when the leaf 11 is lowered for operating the main part of the camera, as shown in Figs. 1 to 4, inclusive.

The partition 27 terminates forwardly in a downwardly turned flange 37, far enough back to not interfere with the closing of the leaf 11 in the usual manner; and about

midway toward the rear, this partition 27 has a transverse depression 38. A shutter 39 is joined to a plate 40 by a hinge 41 that extends transversely in the transverse depression 38; the plate 40 being fixed to the top of the forward part of the partition 27, and having its front end part 42 bent down at a slight angle over the front of the partition 27. A spring 43 is coiled around the pivot of the hinge 41, and engages with the bottom of the depression 38 and with the lower side of the shutter 39, in such a way as to normally hold the shutter across the space between the partition 27 and the partition 6; the shutter being inclined upwardly and rearwardly at a low angle. The partition 6 is provided with a transverse raised part 44 near its rear edge, which receives in its hollow lower side the upper edge of the shutter 39 when it is in the above described position.

A piece 45 of light-transmitting material, such as glass, is mounted in the rear end of a frame 46; this piece 45 being of suitable height to receive the indicating marks, and preferably as wide as the main exposure of the film; and the frame 46 being proportioned accordingly in cross-section. This frame 46 is designed to be pushed back in the operating space 28, depressing the shutter 39 until said shutter lies flat against the upper side of the rear part of the partition 27; this backward movement being continued until the rear surface of the piece 45 is brought close enough to the sensitized surface of the film 33 where the film is supported against rearward displacement by the forwardly pressed part 31 to cause a practically sharp image of the marks to be produced in the sensitized surface by the action of light passing to said surface past the marks. The frame 46 is made the full length from front to rear, of the operating space 28; and its front end is provided at opposite sides with forwardly projecting handles or finger pieces 47 that project out of this space when the frame has been pushed back as far as it will go, as above described.

The piece 45 has its top, bottom and ends beveled convergingly from front to rear, and the frame 46 has a bead 46' pressed in all along its top, bottom and one side to form a stop for the front side of the piece 45, while the upper parts of the frame, to the rear of this bead, are bent in onto the beveled edges of the piece 45, and thus hold it in the frame. One of the handles or finger pieces 47 forms the other end of the rear of the frame, being bent in over the beveled end of the piece 45, with a bead 47' in front of the piece, and allowing this piece 45 to be readily slid out of the frame endwise after this handle has been detached from the side of the frame and withdrawn through the front thereof. The handle is detachably held to said side 130

of the frame by screws 47''. It will thus be seen that the rear end part of the frame 46 is wedge shaped.

The rear surface 45' of the piece 45 is 5 ground, and will readily receive the marks A (Fig. 2) of an ordinary pencil or other convenient writing means; and the front surface 45'' of this piece is also preferably ground or frosted, to diffuse the light in its 10 passage to the sensitized surface.

On the flat upper end of the camera is the receptacle 48 for the frame 46, having its open front end set back from the front side of the camera so that the finger pieces 47 of 15 the frame 46 may project therefrom without projecting past the front side of the camera; and having on its rear end a small door 49 hinged along its top and having a spring 49' that will hold the door closed or 20 hold it raised for access to the rear surface 45' of the piece 45, when the frame 46 is held in the receptacle 48. This frame 46 is thus held by a suitable spring latch 50 that lies in a recess 51 pressed in the top and front upper 25 per corner of the shell 4 at the middle thereof. Thus, the inscription may be made on the rear surface of the piece 45 while it is conveniently held in the camera, and with the entire area of the back of the camera 30 affording a rest for the hand and arm. The frame 46 is then withdrawn from the receptacle 48 and inverted, and then inserted in the operating space 28 in the manner above described, whereupon a negative copy of the 35 inscription is recorded on the sensitized surface by the action of the light shining through the transparent material around and past the more opaque marks A of the inscription on said piece 45.

40 I insure inversion of the frame 46 by beveling its sides 52 (Figs. 1 and 2) and correspondingly beveling the inner sides 53 of the holder 48 in one direction, and the sides 54 of the operating space 28 in the other direction.

45 The inner sides 53 of the holder 48 are preferably formed integral with the main sheet metal part of the holder; but the sides 54 of the operating space may be small pieces fixed to the wooden sides 2 and 3, and being preferably made of wood. These sides 54 terminate at and conform with the upper surface of the shutter 39 in its raised or closed position, and thus form lateral ledges 54', along with the top ledge 44' formed by the raised part 44, for the shutter 39 to abut. To the rear of the shutter, the sides 55 of the operating chamber are merely straight; and the upright parts 26 extend up 50 as far as the lower side of the partition 6, to form fixed rear ends for the operating chamber at the sides, where not occupied by the piece 45 and its frame 46, when these 55 are pushed into operating position. It will be understood that the beveled sides 54 are

long enough, and the frame 46 fits them accurately enough, to insure proper guidance and steadiness of the frame while it is being inserted and after it is brought into operative position; causing the transparent 70 piece 45 to come parallel with or squarely against the sensitized surface.

To properly prevent the entrance of light around the outside of the frame 46, the lower side of the partition 6, the top of the plate 75 40, and the sides 54 are preferably all covered with a soft cushioning material 56, such as soft leather; which thus forms a lining for the operating chamber 28 in its front part. This lining 56 continues back across 80 the ledges 54' on rear ends of the sides 54, and the ledge 44' in the raised part 44; and the upper surface of the shutter 39 also has a covering 57 formed of a continuation of the lining 56 on the plate 40. Thus, there 85 are contacting surfaces of this soft material all around the abutment of the shutter 39.

This covering material 56 extends down onto the inclined part 42 of this plate 40; and at the top the material 56 is preferably 90 continued up into the off-set 10. Since the frame is wedge-shaped at top, bottom and sides on its rear end, it readily enters the operating chamber between the linings 56 thereof where they flare out from the chamber at the front end as just described, and will readily slide over the lining 57 on the top of the shutter 39.

In the insertion of the frame 46 into the operating chamber 28, the shutter 39 is of 100 course pressed wide open as soon as the rear end of the frame 46 has slightly passed the hinge 41 of the shutter. This, therefore, is some time before the piece 45 has come into complete operative position in photographic proximity with the sensitized surface; and during the interval from the opening of the shutter until this complete operative position has been reached, there will, nevertheless, be some passage of light 105 through the piece 45 to the film. I find in practise, that with the piece 45 made of translucent material, or roughened or frosted, or otherwise treated to make it translucent and reduce the quantity of light passing through it to a proper degree, and to properly diffuse this light, there is no appreciable premature action on the sensitized surface; and, at the same time, the printing after the complete operative position has 110 been reached is accomplished in a conveniently short time. In addition to being made translucent, the piece 45 may be of a suitable 115 color to eliminate some of the light rays. I find that ordinary red glass operates very satisfactorily in this respect; and even blue glass is superior to white or clear glass.

To insure against the passage of any light from the operating chamber to the winding chamber 6 between the roller 35 and the rear 120 130

end of the partition 6, a strip 58 of flexible material, such as soft leather, may be mounted on the upper side of the raised part 44 bearing against the roller 35, across the space between it and the partition 6. It will be understood that this precaution is advisable, because the light coming through the operating chamber 28 is diffused through the edges of the piece 45.

10 The use of the light-admitting part or light-transmitting piece with the positively inscribed indicating mark, produces a negative mark on the negative which is fully adequate for its use in conjunction with the negative as distinguished from the prints made therefrom; and which has the additional advantage of producing a positive mark on the print made from the negative. The inscription is made on the surface of

15 the light-transmitting piece with no more precaution necessary than in any ordinary writing; and, if an error be made, it is as readily erased and corrected as it is in the course of any ordinary writing.

20 25 With such advantages as these, there are no attendant disadvantages in practise. The bearing of the masking piece 30 on the sensitized surface of the film, and the slight interval of light admission prior to complete operative positioning of the light-admitting part relative to the sensitized surface, are theoretically disadvantageous; but practically they are not disadvantages, and afford the advantages, in the case of the soft flexible parts bearing against the sensitized surface, of minimizing the width of empty space between the bottom of the picture and the top of the indicating mark; and, in the case of the theoretically premature light admission, of making unnecessary any complex mechanism for controlling the admission of light.

30 35 40 45 50 55 60 65 70 75 80 85 90 95 100 105 110 115 120 125 130

It will be understood that my invention is susceptible to considerable modification in adapting it to cameras of different types and designs, and that while I have illustrated and described in detail a specific example of embodiment of my invention in a camera of well known design, I do not limit myself to this illustration and description, but what I claim as new and desire to secure by Letters Patent is:

1. Means to mark a sensitized surface comprising a light-admitting element with a mark on one side, means whereby said side with the mark may be brought into photographic proximity with said surface, means for controlling admission of light to said surface past said mark, whereby light is excluded from said part of said surface except for short periods during approach and recession of said mark toward and away from said part of said surface, and means impeding the action of said light sufficiently to prevent material action thereof on said

part of said surface during said periods, but permitting the desired action of the light thereon while said mark is for a longer period held in said photographic proximity to said part of said surface.

2. Means to mark a sensitized surface comprising a piece of light-transmitting material treated to reduce its conductivity to light, with a mark on one side, means whereby said side with the mark may be brought into photographic proximity with said surface, means for controlling admission of light to said surface past said mark, whereby light is excluded from said part of said surface except for short periods during approach and recession of said mark toward and away from said part of said surface, said light-transmitting material impeding the action of said light sufficiently to prevent material action thereof on said part of said surface during said periods, but permitting the desired action of the light thereon while said mark is for a longer period held in said photographic proximity to said part of said surface.

3. A holder to hold material having a sensitized surface, and having means to expose part of said surface to receive an image projected thereon, said holder having an operating space distinct from said means, and exposing another part of said surface, a light-admitting element bearing an indicating mark, inserted into said space with said mark in photographic proximity to said surface, and means to control the admission of light to the part of said surface exposed in said operating space, operated by said light-admitting element.

4. A holder to hold material having a sensitized surface, and having means to expose part of said sensitized surface to receive an image projected thereon, said holder having an operating space distinct from said means, and exposing another part of said surface, means comprising a light-admitting element bearing an indicating mark, inserted into said space with said mark in photographic proximity to said surface, and a shutter yieldably held across said operating space to prevent the admission of light to said part of said surface, and engaged by said means comprising the light-admitting element upon insertion thereof, and thereby moved to admit light to the part of said surface exposed in said operating space.

5. A holder to hold material having a sensitized surface, and means at the front of the holder to expose part of said surface to receive an image projected thereon, said holder having an operating space distinct from said means, and opening from the front of said holder to expose another part of said surface, an element so treated that it causes this other part of said surface to be affected differentially by a suitable concomitant agent

when in controlling proximity to said part of said surface, inserted into said space within mechanically unobstructed immediacy to said part of said surface, and means to control the admission of light to the part of said surface exposed in said operating space.

6. A holder to hold material having a sensitized surface, and means at the front of said holder to expose part of said surface to receive an image projected thereon, said holder having an operating space distinct from said means, and opening from the front of said holder to expose another part of said surface, a light-admitting element bearing an indicating mark, inserted into said space with said mark in photographic proximity to said surface, and means to control the admission of light to the part of said surface exposed in said operating space.

10 7. A holder to hold material having a sensitized surface, and means at the front of said holder to expose part of said surface, to receive an image projected thereon, said holder having an operating space distinct from said means, and opening from the front of said holder to expose another part of said surface, a light-admitting element bearing an indicating mark, inserted into said space with said mark in photographic proximity to said surface, and means to control the admission of light to the part of said surface exposed in said operating space.

20 8. A holder to hold material having a sensitized surface, and means at the front of said holder to expose part of said surface, to receive an image projected thereon, said holder having an operating space distinct from said means, and opening from the front of said holder to expose another part of said surface, a light-admitting element bearing an indicating mark, inserted into said space with said mark in photographic proximity to said surface, and means in said operating space to control the admission of light to the part of said surface exposed in said operating space.

30 9. A holder to hold material having a sensitized surface, and means at the front of said holder to expose part of said surface, to receive an image projected thereon, said holder having an operating space distinct from said means, and opening from the front of said holder to expose another part of said surface, means comprising a light-admitting element bearing an indicating mark, inserted into said space with said mark in photographic proximity to said surface, and a shutter yieldably held across said operating space to prevent the admission of light to said part of said surface, and engaged by said means comprising the light-admitting element upon insertion thereof, and thereby moved to admit light to the part of said surface exposed in said operating space.

40 10. A holder to hold material having a sensitized surface, having means to expose part of said surface to receive an image projected thereon, said holder having an operating space distinct from said means in which another part of said surface is exposed, a light-admitting part element carrying an indicating mark to bring said mark into photographic proximity to said part of said surface exposed in said operating space, and means for controlling admission of light through said operating space to said surface past said mark, whereby light is excluded from said part of said surface except for

short periods during approach and recession of said mark toward and away from said part of said surface, said light-admitting element comprising means impeding the action of said light sufficiently to prevent material action thereof on said part of said surface during said periods, but permitting the desired action of the light thereon while said mark is for a longer period held in said proximity to said part of said surface.

70 11. A holder to hold material having a sensitized surface, and having means to expose part of said surface to receive an image projected thereon, said holder having an operating space distinct from said means, and exposing another part of said surface, a light-admitting element bearing an indicating mark, inserted into operative position in said space with said mark in photographic proximity to said surface, means to control the admission of light to the part of said surface exposed in said operating space, and a receptacle on said holder for said light-admitting element having an opening through which said mark may be applied to said element, said receptacle and said light-admitting element being so relatively shaped that said element can be inserted in said receptacle for exposure through the opening thereof in only one position relative to said receptacle, and means whereby said element can be inserted into said operating space in only one operative position relative to the part of said surface exposed in said operating space.

80 12. A holder to hold material having a sensitized surface, and having means to expose part of said surface to receive an image projected thereon, said holder having an operating space distinct from said means, and exposing another part of said surface, a light-admitting element bearing an indicating mark, inserted into operative position in said space with said mark in photographic proximity to said surface, means to control the admission of light to the part of said surface exposed in said operating space, and a receptacle on said holder for said light-admitting element, having an opening through which said mark may be applied to said element, said receptacle and said light-admitting element being so relatively shaped that said element can be inserted in said receptacle for exposure through the opening thereof in only one position relative to said receptacle, and means preventing insertion of said element into said operative position in said operating space except after inversion from its position in said receptacle.

85 13. In a camera, a holder to hold material having a sensitized surface presented toward the front of the camera, means opening through the front of the camera to expose part of said surface to receive an image projected thereon, said camera having an

- operating space open from the front of said camera, above said opening, through which another part of said surface is exposed, masking means bearing against said surface 5 between the part exposed through the operating space and the part on which the image is projected, a light-admitting element bearing an indicating mark, inserted into said space with said mark in photographic proximity to said surface, means to control the admission of light to said part of said surface exposed in said operating space, and a receptacle for said light-admitting element on the top of said camera, having an 10 opening for exposure of said element whereby said mark may be applied to said element, said receptacle and said element being so relatively shaped that said element can be inserted in said receptacle for said 15 exposure through the opening thereof in only one position relative to said receptacle, and means preventing insertion of said element into said operating space with said mark in said proximity to the surface, except after inversion from its position in said 20 receptacle.
13. A holder to hold material having a sensitized surface, and having means to expose part of said surface to receive an image projected thereon, said holder having an 25 operating space distinct from said means, and exposing another part of said surface, and having an inwardly presented ledge in its interior, means comprising a light-admitting element bearing an indicating mark, inserted into said space past said ledge, with said mark in photographic proximity to said surface, and a shutter yieldably held 30 across said operating space and overlapping said ledge, to prevent the admission of light 35 to said part of said surface, and engaged by said means comprising the light-admitting element upon insertion thereof, and thereby moved to admit light to the part 40 of said surface exposed in said operating space.
14. A holder to hold material having a sensitized surface, and having means to expose part of said surface to receive an image projected thereon, said holder having an 45 operating space distinct from said means, and exposing another part of said surface, and having sides terminating inwardly of said space in inwardly presented ledges, means comprising a light-admitting element bearing an indicating mark, inserted into operative position in said space past 50 said ledges with said mark in photographic proximity to said surface, and a shutter yieldably held across said operating space 55 and overlapping said ledges, to prevent the admission of light to the part of said surface exposed in said operating space, and engaged by said means comprising the light-admitting element upon insertion thereof, 60 and thereby moved to admit light to the part of said surface exposed in said operating space, and a receptacle on said holder for said means comprising the light-admitting element, having an opening through 65 which said mark may be applied to said element, said receptacle and said means comprising the light-admitting element being so relatively shaped that said means comprising the light-admitting element can be 70 inserted in said receptacle for exposure through the opening thereof in only one position relative to said receptacle, said sides of said receptacle being so shaped relative to said means comprising the light-admitting element that this means can be inserted into said operating space in only one operative position relative to the part of said surface exposed in said operating space. 75
